UNITED STATES PATENT OFFICE

2,672,698

FORM-FITTING SOCK LINING

Carlisle V. Watson, Auburn, Maine

Application November 29, 1952, Serial No. 323,184

1 Claim. (Cl. 36—71)

1
This invention comprises a new and improved form-fitting sock lining for shoes having pronounced transverse curvature at the inside shank portion for supporting the arch of the wearer's foot.

The problem of providing a flexible sock lining that will lie flat in the bottom of a shoe provided with an upwardly projecting support or cookie for the inner longitudinal arch of the foot was solved to a large degree by the invention of my prior Patent No. 2,413,534 dated December 31, 1946. That patent describes the expedient of providing a sock lining with a cookie insert piece larger in its area than the projected area which it is to cover in the inside shank curve of the sock lining and by securing such insert so as to throw a spring into it causing the insert piece normally to stand up in a convex curve while the body of the sock lining lies flat on the flatter surface of the shoe bottom. A sock lining so constructed is given the necessary three dimensional contour required to fit smoothly upon an underlying insole having an arch supporting formation.

While the sock lining of my said prior patent has been entirely satisfactory in structure and has remained smooth and free of wrinkles in wear, it necessitates considerable additional shoe-making expense and requires the services of skilled operators in its production. The present invention is based on my discovery that the desired results may be secured at considerably less cost by utilizing a sock lining having a continuous integral body with an inside shank portion extending outwardly in a cookie extension and being set off and defined from the body of the sock lining by a curved line of pronounced indentations. This line of indentations provides, in effect, a hinge line connection and a stiffening ridge between the body of the sock lining which conforms only to the longitudinal curvature of the shoe bottom and the cookie extension which constitutes a prominence sloping upwardly above the plane of the body of the sock lining and which must present a smooth three dimensional curvature.

The improved sock lining of my invention accordingly obviates the necessity of providing separate cookie inserts and eliminates the operation of attaching the insert in a sprung or distorted condition. On the other hand, it achieves all the desired results and provides a form-fitting sock lining which may be produced from an integral blank by a single stamping, molding or embossing operation.

These and other features of the invention will

be best understood and appreciated from the following description of a preferred embodiment thereof, selected for purposes of illustration and shown in the accompanying drawings in which:

5 Fig. 1 is a plan view of the flat blank,
Fig. 2 is a similar view of the finished sock lining, and
Fig. 3 is a sectional view on the line 3—3 of Fig. 2 but on an enlarged scale, showing in addition an underlying pad.

The sock lining may be cut from calf upper leather, or from composite fibre, or any flexible sheet material commonly used in the industry for sock linings. It is of conventional shape having the outline of an insole with a forepart 10, heel portion 11 and with the addition that its inside shank portion is extended outwardly in a cookie extension 12 of convex edge contour. The blank is normally flat and is represented in Fig. 1 with its grain or finished surface uppermost as it is eventually positioned in the shoe.

The sock lining is completed by placing the blank in the proper location between suitable molding dies which are constructed and arranged to form a curved line 13 of separate, repeated and pronounced indentations. This line 13 coincides with the normal inside shank curvature of the corresponding insole and forms in effect a curved hinge line of connection between the flat body of the sock lining and the cookie extension 12. The molding operation which is effected by the molding dies simultaneously with the formation of the indented line 13 fashions the cookie extension 12 into an upwardly convex prominence of smooth uniformly curved contour, with a downwardly extending stiffening ridge in the line of indentations. This closely approximates the contour of the arch supporting pad 14 or other support which is located beneath it in the shoe bottom as indicated in Fig. 3.

45 A shank fitting pad 14 of convex curvature may be assembled in the shoe bottom by being cemented to the extension 12 of the sock lining, or it may be independently secured before the sock lining is placed in position. In other cases the arch supporting section will be molded into the insole itself, but in whatever manner the transverse supporting curvature is secured in the shoe bottom it will be smoothly fitted by the improved sock lining of my invention.

The present application is filed as a substitute for and continuation-in-part of my prior application, Ser. No. 186,219 filed September 22, 1950, now abandoned in favor of the present application.

Having thus disclosed my invention and described in detail a preferred embodiment thereof, I claim as new and desire to secure by Letters Patent:

An improved form-fitting sock lining for shoes having both longitudinal and transverse curvature at the inside shank portion for supporting the inner longitudinal arch of the wearer's foot, said lining comprising a continuous integral body of thin flexible sheet leather with a grain surface and having the contour of the insole with its inside shank portion extending outwardly in a cookie extension of convex edge contour, the said extension being set off and defined from the body of the sock lining by a curved line of separate and repeated indentations in its foot en-

10 gaging grain surface providing a hinge line connection and a downwardly extending stiffening ridge, the extension being shaped as a convex prominence sloping upwardly above the plane of the body of the sock lining, and an arch fitting pad of convex upward curvature secured to the under face of the said extension.

CARLISLE V. WATSON.
